UNITED STATES PATENT OFFICE.

GEORGES LAKHOVSKY, OF PARIS, FRANCE.

APPARATUS FOR THE RECEPTION AND TRANSMISSION OF SOUND.

Application filed May 14, 1924, Serial No. 713,295, and in France November 29, 1923.

The known apparatus for the reception or transmission of sound are generally formed by a metal box or case wherein there is a vibratory diaphragm or plate which is in contact with this box and which also encloses the electric parts, such as magnets or electro-magnets in the case of receiving apparatus, or pieces of carbon (e. g. carbon granules) and their supporting means, envelopes, etc., in the case of transmitting apparatus.

From this it results that on the one hand by reason of the contact of the plate with the box or case, the vibrations of the plate are partially transmitted to the box or case, the resonance of which causes parasitic noises, which impair the purity of the sound. On the other hand this injurious effect is further increased by the setting in vibration of the box or case under the effect of the operation of the interior electric parts.

This invention has for its object to obviate this disadvantage by preventing the formation of these parasitic noises, in such a manner that the sounds emitted or transmitted shall not be impaired and shall be perfectly pure.

This invention is characterized essentially in that the vibratory diaphragm or plate on the one hand and the internal electric parts on the other hand (magnets or electro-magnets in the case of receiving apparatus, or pieces of carbon and their support or envelope in the case of transmitting apparatus) are isolated from the box or case enclosing these parts and from the cover thereof, in such a manner that the plate shall be shielded from any parasitic vibrations of the box or case, of the electric parts which it encloses, of the cover, and of the horn or amplifier mounted on the latter. Under these conditions the sounds produced are absolutely pure.

This invention moreover has for its object means for carrying it into practice. Such means for carrying the invention into practice is characterized more especially by the following points:—

1. The vibratory plate or plates is or are mounted through the medium of a ring of india rubber or other suitable material on a box or case having a double wall, the annular space of which is filled with a material capable of damping vibration, such as paraffin, oil or the like.

2. The internal electric parts (magnets or

electromagnets in the case of receiving apparatus, or pieces of carbon and their envelope or support in the case of transmitting apparatus) are arranged in a box adjustably mounted in the interior of the double walled box or case, which by its special construction is without resonance and thus completely isolates these parts from the plate or plates.

3. Preferably this box or case is covered with a plate serving to prevent any reciprocal action of the mass of air surrounding the interior electric parts and the mass of air in direct contact with the vibratory plate.

This invention is shown by way of example only in the accompanying drawing, in which it is assumed to be applied to a telephonic receiver.

Figure 1 is a vertical section.

Figure 2 is another section taken on a plane perpendicular to that of the preceding view.

Figures 3 and 4 illustrate two modifications.

As shown in this drawing, the vibratory diaphragm or diaphragms *a* are framed in an india rubber ring *b* which is itself held fast between a shoulder *c* on the body of the apparatus and the rim *d* of the cover.

The electromagnets *e* are mounted in a cylindrical box *f*. This box is capable of sliding in the cylindrical recess formed by the interior wall *h* of a double-walled box or case *i*. The space *j* is filled with paraffin or other suitable material. The latter is introduced through apertures *k* which can be afterwards closed by small screw plugs.

The position of the box *f* is determined by a screw *l* which is fixed thereto and which extends through a nut *m*. The latter bears on its periphery a helical thread with which gears a worm *n* controlled from the exterior by means of a milled head *o*. It will be readily understood that by operating this milled head the nut *m* is turned and the screw *l* and with it the box *f*, is caused to rise or fall, which enables the position of the box and consequently that of the electromagnets to be adjusted relatively to the vibratory plate.

It is obvious that the adjusting means described can be replaced by rack and pinion or any other suitable mechanism.

The box *f* is preferably covered by a plate *g* serving to prevent any reciprocal action of

the mass of air surrounding the internal electric parts, and the mass of air in direct contact with the vibratory plate.

The cover *p* is also double-walled and filled with paraffin or other suitable material. It is traversed by a tube *q* for permitting the exit of the waves, and on which a horn can be fitted.

In the modification illustrated in Fig. 3, the ring *b* is retained by a metallic washer *f* screwed within the flange of the cover. The screw threaded portion of the cover serves also to screw the latter on the body *i*. It results therefrom that by screwing or unscrewing the cover, it is possible to adjust the distance separating the electromagnets *e* from the plate *a* and that the mechanism *l m n o* of the previous arrangement shown in Figs. 1 and 2 can be done away with.

The washer *f* can be replaced by a plate *r*, Fig. 4, having a central opening *s* for the passage of the electromagnet; this arrangement has the advantage of reducing the volume of air which is under the plate. The diaphragm or plate *a* is set in a metallic mounting *t* isolated by two india rubber washers *u* and *v*.

By reason of the above conditions the vibratory diaphragm or plate is shielded from any parasitic vibrations which may come either from the case or from the horn, or from the elements or parts such as electromagnets, etc., causing the movement of such diaphragm or plate. In fact the vibratory movements of the diaphragm or plate cannot be communicated to the case by reason of the isolation ensured by the india rubber ring *b* and of the presence of the damping material within the double wall *i*. Conversely, vibrations or noises which may be produced by the operation of the exterior parts are also suppressed. The double walled cover damps the vibrations of the horn.

Under these conditions, the diaphragm or plate *a* alone vibrates and the sounds cannot lose their natural quality by any parasitic noise and are absolutely pure.

The apparatus can be completed by a horn having a double wall filled with a damping material. This arrangement of the horn completes the effect of the double-walled cover and of the bores filled with damping material.

The new arrangements are especially applicable to loud speakers used in wireless telephony.

The above arrangements are obviously only given by way of example, the forms, dimensions, materials employed and all detail arrangements can be varied in all cases without departing from the nature of the invention, as defined in the appended claims.

Claims:—

1. In an apparatus for the reception and transmission of sound, a vibratory membrane, parts for causing this membrane to vibrate, a box enclosing the membrane and said parts, a double side in this box containing a material damping the vibrations, a hollow cover also containing a material damping the vibrations. 65

2. In an apparatus for the reception and transmission of sounds, a vibratory membrane, parts for causing this membrane to vibrate, a box enclosing the membrane and said parts, a double side to this box containing a material damping the vibrations, a hollow cover also containing a material damping the vibrations, a tube through the cover for the passage of low sound waves. 75

3. In an apparatus for the reception and transmission of sound, a vibratory membrane enclosed in a rubber ring, parts causing this membrane to vibrate, a box enclosing the membrane and the said parts, a double side to this box containing a material damping the vibrations, and hollow cover also containing a material damping the vibrations. 85

4. In an apparatus for the reception and transmission of sound, a vibratory membrane enclosed in a rubber ring, parts to cause this membrane to vibrate, a box enclosing the membrane and the said parts, a double side to this box containing a material damping the vibrations, a hollow cover also containing a material damping the vibrations, enclosing the rubber ring between the cover and the box. 95

5. In an apparatus for the reception and transmission of sound, a vibratory plate, parts for causing this plate to vibrate, a double-walled box containing a substance that damps vibrations, a double-walled cover for the said box, filled with a material that damps vibrations. 105

The foregoing specification of my "Improvements in apparatus for the reception and transmission of sound" signed by me this 30 day of April, 1924.

GEORGES LAKHOVSKY.
